UNITED STATES PATENT OFFICE

HERMAN WESSELS, OF LOUISVILLE, KENTUCKY

DAMPER CONTROL

Application filed November 17, 1930. Serial No. 496,241.

This invention relates to certain new and useful improvements in damper controls of the thermostatically operable type.

Another object of the invention consists in the provision and arrangement of adjustable means to regulate the amount to which the damper is to be opened pursuant to the desired degree of temperature to be maintained.

With the above and other objects in view, the invention further consists of the following novel features and details of construction, to be hereinafter more fully described, illustrated in the accompanying drawings and pointed out in the appended claim.

In the drawings:—

Figure 1 is a side elevation of a form of furnace disclosing the relative arrangement of the several forms of the present invention upon the ash pit and flue pipe dampers.

Figure 2 is a sectional view taken on line 2—2 of Figure 1.

Figure 3 is a side elevation of a modified form of the invention partly broken away.

Figure 4 is an end elevation of the modification.

Figure 5 is a perspective view of an adjustable element for the modification.

Figure 6 is a view similar to Figure 3 of another form of my invention.

Figure 7 is an end elevation of the Figure 6 modification partly broken away to illustrate the relative arrangement of the damper adjusting means.

Referring to the drawings in detail wherein like characters of reference denote corresponding parts, the reference character 10 indicates generally a form of furnace having a damper 11 swingably supported upon the

ash pit door 12 and a check draft damper 13 correspondingly mounted upon the furnace flue pipe 14. All of the above is of the usual and well known construction and which forms no part of the present application for Letters Patent and is mentioned for purposes of illustration only in bringing forward the novel advantages of the present invention.

The invention primarily resides in the provision and arrangement of thermostatic elements 15 which may be arranged in any one

of the several positions suggested for coaction with the fluctuations in temperature.

The installation of the thermostat 15 upon the flue pipe 14 necessitates the employment of an arcuate-shaped attaching plate 21 riveted or otherwise secured upon the flue pipe in the manner suggested in Figure 3. An arm 22, carried by and upwardly, outwardly and obliquely inclined from the attaching

plate, terminates to provide a bifurcated portion 23 within which the component portions of the thermostat are positioned. An arm member 24, carried by and outwardly projecting from the attaching plate 21, has pivotally mounted thereon a fulcrum lever 25

having a flexible connection 26 between one end thereof and the check draft damper 13. An adjusting screw 27, carried by the fulcrum lever 25 and within the remaining end thereof, is adjustably positioned at right

angles thereon for coacting engagement with the extended portion of the thermostat 15 whereby the position of the check draft damper may be regulated.

From the foregoing it is obviously apparent that the flexing of the thermostat will open and close the dampers in accordance with the fluctuations in temperature.

The modified form of my invention disclosed in Figures 1 and 3 to 5 inclusive may be either arranged directly upon the furnace, as shown in Figure 1, or installed as a remote control. The modification consists of a housing structure 28 having a thermostat 29

horizontally positioned therein and disposing the free end thereof across the points of communication between the housing proper and a depending extension 30 therefor. A fulcrum lever 31, pivotally mounted upon a tongue 32 carried by and depending from the

housing 28 is projected at one end within the housing extension 30 through one of a pair of vertically aligned slots 33 in the adjacent side wall thereof. A connecting rod 34 having

adjustable connection at one end with the thermostat 29 is projected within the housing extension 30 to swivelly accommodate the hook end 35 thereof within an eye 36 positioned upon the upper surface of a guide

element 37. Extensions 38 carried upon the

50 55 60 65 70 75 80 85 90 95 100

guide element 37 are disposed within the slots 33 in the housing extension 30 whereby the element 37 may be shifted rectilinearly therethrough. A sleeve member 39, adjustably positioned upon the connecting rod 34, has a set screw 40 projecting therefrom for accommodation within the slot 41 formed within the forked extremity of the fulcrum lever 31. A counter-balancing weight 42 is adjustably positioned upon the fulcrum lever 31 for coaction with the thermostat 29 and guide member 37 in a manner to be better understood in the following description of the invention. A shaft member 43, journaled within aligned openings 44 in the guide element 37 upon opposite sides of a cut-out portion 45 therein, carries a connector 46 having a crank arm 47 projecting therefrom and to which one end of a flexible connector 48 in the nature of a chain or the like is attached. A disk member 50 fixedly positioned upon an extended portion of the shaft 43 beyond the wall of the housing extension, is calibrated and notched. The notches in the disk 50 correspond to the calibrations whereby the apparatus may be set to automatically maintain a predetermined temperature. As a matter of fact the notches in the disk 50 may correspond to the outside temperature for opening the drafts of the furnace sufficiently to maintain an even heat of 70°.

In accomplishing the foregoing, I provide a lever member 51 pivotally mounted, as at 35 52, for rocking motion upon one of the extensions 38, and having a projection 53 upon one end designed for accommodation within any one of the aforementioned notches in the disk 50 while a retractile spring 54 establishing connection at its ends between the aforementioned extension 38 and the other end of the lever 51 yieldingly retains the aforementioned extremity 53 within the prescribed notch.

45 In Figures 6 and 7 of the drawings, I have illustrated another modification of the invention which, as shown, combines the major characteristics of the other forms of the invention in that adjustment is afforded to both 50 the thermostat and fulcrum bar. The foregoing characteristics of construction is facilitated through the employment of a housing 55 having a thermostat 56 transversely positioned therein adjacent the closed end wall 55 thereof. The other end of the housing, after the manner of the housing extension 30 for the housing 28 in the modified form of the invention disclosed in Figures 4 to 6 inclusive, has the lowermost end open to facilitate ingress of air. A supporting arm 57 positioned within the housing 55 and depending therein in spaced relation to the walls thereof has pivotally supported thereon a fulcrum lever or bar 58 including a counter-balanced weight 59. An adjusting screw 60, carried upon one

end of the lever 58 is designed for coacting engagement with the free end of the thermostat 56 whereby the position of the drafts may be thermostatically controlled in an effective and expeditious manner for the maintenance of predetermined temperature. 70

From the foregoing, it is understood that flexing of the thermostat through the expanding and contracting thereof, caused by fluctuations in temperature, will open and close 75 the dampers in the manner set forth.

The invention is susceptible of various changes in its form, proportions and minor details of construction and the right is herein reserved to make such changes as properly 80 fall within the scope of the appended claim.

Having described the invention what is claimed is:

A damper control comprising a support, a thermostat detachably mounted in the support, a connecting rod adjustably attached to the thermostat and housed within the support, a lever pivoted to the support and connected at one end with said rod, a weight adjustable upon the lever and located exteriorly of the support, a guide member slidable in the support and connected with the connecting rod, a shaft journaled in the guide member, a chain arranged to wind upon said shaft and adapted to be connected with a damper, a disk fixed 90 to the shaft and provided with peripheral notches, and a lever member pivoted upon the guide member and having an end adapted to enter the notches. 95

In testimony whereof I affix my signature. 100
HERMAN WESSELS.
